LIPSTICK CASE

Daniel Marc Sée, Ridgefield, Conn.

Application November 26, 1941, Serial No. 420,458

5 Claims. (Cl. 206—56)

The present invention relates to improvements in cosmetic containers, and relates more particularly to an improved type of retractable lipstick case.

The main object of my invention is to provide an improved type of retractable lipstick case wherein a refill may be conveniently inserted after the original lipstick has been used up.

Presently, in the refillable type of retractable lipstick case, after the initial lipstick cartridge has been consumed, in order to replace this with a refill, the remainder or remnants of the old lipstick must be scooped or scraped out of the lipstick holder with a knife, spatula or the like. This, at its best, is troublesome and often entails and involves obvious undesirable consequences.

It is therefore another object of the present invention to provide a retractable lipstick case of the refillable type wherein the remainder of the consumed lipstick may be simply, readily and conveniently removed in order that a refill cartridge may be properly inserted therein.

Another object of my invention is to provide a retractable lipstick case of the swivel or other type wherein the remains of the old lipstick may be conveniently removed through the bottom of the case and replaced by a refill cartridge.

Still another object of my invention is to provide a retractable lipstick case of the swivel or push type wherein the bottom cap or wall of the case is removable, thus permitting the extraction of the remains of the old lipstick and its holder and the subsequent insertion of a refill.

A further object of my invention is to provide a lipstick case of the type above set forth wherein the lipstick holder is normally confined within the case and may be removed therefrom only after the parts of said case assume a certain predetermined relative position.

Other objects of my invention will be set forth in the following description and drawing which illustrate preferred embodiments thereof, it being understood that the above statement of the objects of my invention is intended generally to explain the same without limiting it in any manner.

Fig. 1 is a detail sectional elevational view of one embodiment of my improved lipstick case;

Fig. 2 is a sectional view along line 2—2 of Fig. 1;

Fig. 3 is an elevational view of the casing and lipstick holder, showing the adjacent walls of the casing in contracted position;

Fig. 4 is a perspective view of the bottom cap portion of the case;

Fig. 5 is a detail sectional elevational view of another embodiment of my invention;

Fig. 6 is a sectional view along line 6—6 of Fig. 5; and

Fig. 7 is a perspective view of the retractable lipstick holder.

Referring to the drawing and more particularly to Figs. 1—4 thereof, which illustrate the simple form of retractable lipstick case, B designates the body member and C the cover member of said case. The body member B comprises the outer casing 10, the retractable lipstick holder 11 and the bottom capping member 12. The outer casing member 10 is preferably cylindrical in shape although it may assume any desired shape, such as of polygonal or elliptical transverse cross-section, said casing member being open at both ends and having a pair of diametrically opposed longitudinal slits formed in the wall thereof, said slits extending from the bottom of the casing member to points below the top thereof. Formed along the bottom of the casing wall, is the peripheral lip or convexity 14. The casing 10 is made of resilient flexible material such as certain well-known alloys or plastics so that the lower portions of the casing wall which is divided by the slits 13 may be manually forced together and will return to their normal separated position when the pressure is removed.

Slidably positioned within the casing member 10 is the lipstick holder or collar 11, said holder having a transverse cross-section similar to that of the casing 10 and having the bottom portion 16 having the aperture 17 formed therein. Projecting from the vertical wall of the lipstick holder 11 in proximity to the bottom thereof and at diametrically opposite points are the pintles 18, said pintles being slidably engaged by the respective slits 13.

The bottom cap member 12 is of circular shape and has the vertical peripheral wall 20. Formed in the inner face of said peripheral wall 20 is the groove or concavity 21, the surface of said groove 21 having substantially the same contour and shape as the outer surface of the lip or convexity 14 when the divided walls of the casing are in normally expanded position.

The casing 10 should be made of the material hereinbefore set forth while the remainder of the case may be made of any suitable and desirable material such as wood, plastic, metal, etc.

The operation and use of the embodiment above

described and illustrated in Figs. 1-4 of the drawing is both simple and efficient. When the lipstick L has been worn below the upper edge of the holder 11, and can no longer be used, it may be replaced by a refill as follows:

The cover C is removed and the holder 11 raised to its topmost position as shown in Fig. 3, the pintles 18 being positioned in the upper part of slit 13, thus permitting the forcing together of the lip edges of the walls of the casing 10. The divided walls are then manually forced together permitting the removal of cap 12 and the holder 11 is thereafter removed from the casing and discarded. The refill is provided with a holder identical with holder 11 which holder is permanently positioned at the end of the refill. The holder and the new lipstick are then returned to the casing and raised to its upper position, the lower edges of the casing walls forced together and the bottom cap fitted thereon. Upon releasing the pressure on the casing, the lower edges return to their normally expanded position and the lip 14 snugly engages the groove 21. When the holder 11 is below its topmost position relative to the casing, the pintles 18 maintain and substantially lock the walls of the casing in their expanded position, thus preventing the removal of the bottom cap 12.

In Figs. 5-7, there is shown my invention as applied to the swivel type of retractable lipstick case. The body member consists primarily of an outer casing 32, intermediate casing 33, inner casing 34, the retractable lipstick holder 35 and the bottom cap member 36.

The outer casing is cylindrical in shape and has formed along its upper edge the inwardly projecting flange 37. Rigidly fitted within the outer casing 32 is the intermediate casing 33, said intermediate casing having the helical slit 38 and the longitudinal slit 39 formed therein, the former slit opening at the bottom of casing 33 and terminating at a point below the top thereof, and the slit 39 extending the entire length of the casing and meeting slit 38 at the bottom thereof. The intermediate casing 33 is made of a resilient material, the slit 39 allowing the transverse compression of said casing, thus permitting the assembling of the outer and intermediate casings. The upper edge of casing 33 is below the lower face of flange 37, thus forming the peripheral recess 40.

Rotatably mounted within the intermediate casing 33 is the inner casing 34, said casing being longitudinally maintained by engagement of the peripheral recess 40 with the bead 41 formed in the wall of casing 34 near the top thereof. The lower edge of the inner casing 34 has the peripheral shoulder outwardly, laterally extending therefrom, the outer edge of said shoulder having the depending flange 43. A longitudinal slit 44 is formed in casing 34, which slit starts at 42 and terminates at a point below the top of the inner casing.

Slidably mounted within the inner casing 34 is the lipstick holder 50, said holder having the cylindrical wall 51 and the bottom wall 52, said bottom wall 52 having formed therein the aperture 53. Projecting laterally from the wall 51 near the bottom thereof is the pintle 54, said pintle 54 normally slidably engaging the helical slit 38 and the longitudinal slit 44. The bottom cap member 35 frictionally engages the outer face of the inner casing flange 43 and may be conveniently and manually removed.

The lipstick holder 50 and contained lipstick may be raised or lowered by rotating the inner

casing relative to the intermediate casing, which movement may be performed by rotating the cap member 55 relative to the outer casing. Since the cap member is normally rigid with the inner casing, and the intermediate casing is fixed to the outer casing, the aforementioned relative motion is thus achieved. Further, since slit 44 will intersect helical slit 38 at a level depending upon the relative rotational position of said slits and since the lipstick holder pintle must register with both slits, the longitudinal position of said holder is determined by the relative positions of said slits, which in turn may be manually determined as above described.

In order to replace a depleted lipstick, the holder 50 is brought to its lowermost position at which position the bottom openings of helical slit 38 and slit 44 coincide, thus permitting the removal of holder 50 through the lower end of the case upon removal of the cap 55. The old lipstick is then replaced by a refill cartridge, as described in the first embodiment, the holder and lipstick inserted in the case, the holder pintle registering with the slits 38 and 44 at their bottom openings and the cap 55 reset.

I have shown preferred embodiments of my invention, but it is obvious that numerous changes and omissions and alterations may be made without departing from its spirit.

I claim:

1. A retractable lipstick case of the refillable type comprising a resilient flexible casing member, said casing member having a pair of diametrically opposite longitudinal slits formed therein, said slits extending to the bottom of said casing member, a lipstick holder slidably mounted within said casing member, said lipstick holder having a pair of diametrically opposite pintles projecting from the wall of said holding member, said pintles slidably engaging the longitudinal slots and flexing said casing member, a cap member, said cap member having means adapted to engage the lower edge of said casing member, said cap member being locked in position at the lower end of the casing member when the holder is below its topmost position relative to said casing.

2. A retractable lipstick case of the refillable type comprising a resilient flexible casing member, said casing member having a pair of diametrically opposite longitudinal slits formed therein, said slits extending to the bottom of said casing member, a lipstick holder slidably mounted within said casing member, said lipstick holder having a pair of diametrically opposite pintles projecting from the wall of said holding member, said pintles slidably engaging the longitudinal slots and flexing said casing member, the lower portion of the casing member having a peripheral lateral projection, a cap member, said cap member having a cylindrical wall, said wall having a peripheral groove formed in its inner face, said groove being adapted to engage said casing projection.

3. A device as claimed in claim 2, in which the diameter of the holder pintles is substantially equal to the width of the longitudinal slits.

4. A retractable lipstick case comprising a tubular casing provided with a lengthwise slit opening through one end thereof, an outwardly projecting lip at said one end of said casing member, a removable cap member for said casing member, said cap member including a bottom wall and an annular side wall, said side wall being so formed on the inner side thereof to receive

said lip to thereby lock said cap member on said casing member, a lipstick holder slidable in said casing member, and a pintle fixed to said holder slidable in said slit, said cap member normally closing the open end of said slit, said casing member being compressible at said one end when said holder is positioned adjacent the opposite

end whereby said one end of said casing may be deformed to disengage said lip from said cap.

5. A retractable lipstick case as set forth in claim 4 wherein said lip is formed as an outwardly deformed bead.

DANIEL MARC SÉE.
